DESIGN FOR A POCKET FILE

Leon B. Miller, Brooklyn, N. Y.

Application October 19, 1937, Serial No. 72,304

Term of patent 7 years

To all whom it may concern:

Be it known that I, Leon B. Miller, a citizen of the United States, residing at Brooklyn, in the county of Kings and State of New York, have invented a new, original, and ornamental Design for a Pocket File, of which the following is a specification, reference being had to the accompanying drawing, forming part thereof.

Fig. 1 represents a front view of a pocket file, showing my new design;

Fig. 2 is a side elevation thereof; and
Fig. 3 is a rear view of my pocket file.

The characteristic features of my design reside in the handle and clip portions of the file.

I claim:

The ornamental design for a pocket file as shown and described.

LEON B. MILLER.
